UNITED STATES PATENT OFFICE.

JOHN WRIGHT AND ANDREW WRIGHT, OF ROHNERVILLE, CALIFORNIA.

GATE.

SPECIFICATION forming part of Letters Patent No. 240,567, dated April 26, 1881.

Application filed February 16, 1881. (No model.)

To all whom it may concern:

Be it known that we, JOHN WRIGHT and ANDREW WRIGHT, of Rohnerville, in the county of Humboldt and State of California, have 5 jointly invented certain new and useful Improvements in Gates; and we do hereby declare the following to be a full, clear, and exact description of the invention, such as will enable others skilled in the art to which it pertains to 10 make and use it, reference being had to the accompanying drawings, which form part of this specification.

Our invention relates to an improvement in gates, the object being to produce a double 15 gate the two portions of which are adapted to be operated in opposite directions by automatic mechanism. With this end in view our invention consists in certain details of construction and combinations of parts, as will 20 be hereinafter described, and pointed out in the claims.

In the accompanying drawings, Figure 1 is a view, in perspective, of a double gate as 25 constructed in accordance with our invention. Fig. 2 is a plan view of one of the gate-posts; and Fig. 3 is a view, in vertical section, through the pair of pulleys mounted on one of the posts, to show the device for unlatching the gate.

Let A represent frame-posts, strengthened 30 by flying braces C C. A cross-beam, D, is secured to the top of the two frame-posts A A. Angular braces E, having their upper and lower ends respectively secured to the cross-beam D and frame-posts A A, aid in preserving the 35 desired form of the gate-frame.

Gate-posts F, located opposite each other and just within the frame-posts, are adapted to have vertical axial rotation in the gate-frame. The lower ends of said gate-posts are 40 in this instance provided with a pin, G, which is received and has pivotal movement in a socket, H, embedded in the ground. Aper- 45 tures A', at each end of the cross-beam D, admit the tenoned upper ends of the posts F, and are adapted to permit their free revolu- tions therein.

Gates C', rigidly secured to the posts F, near their lower extremities, partake of the motion of the posts to which they are respectively at- 50 tached, and which, as will be presently shown, revolve in opposite directions.

Pulleys D', having grooved peripheries E', in which is received a flexible connection, F', encircling them, are rigidly secured to that end of the gate-post which projects through the 55 cross-beam D.

In the construction shown the upper ends of the gate-posts are each configurated to form a square block, G', between two circular portions, H' and I, of unequal diameter. The 60 larger, I, of the circular portions of the posts are received in the apertures A' in the ends of the cross-beam, the squared portions G' receive, in rigid adjustment, the pulleys D', while the extreme upper ends of the posts, forming 65 the smaller, H', of the circular portions, are adapted to receive the flanged pulley A², upon which the flexible connection A³, between the counter-weights B², is disposed. Said pulleys also serve to operate the gate-latch, to be here- 70 inafter described.

It is apparent that we need not, of necessity, adopt the precise construction of gate-post shown, but may make formal changes without transcending the spirit of the invention. 75

As has been observed, the pulleys A² are free to rotate on the ends H' of the posts, and consequently do not partake of the motion thereof only through the pulleys D' rigidly secured thereto, and which have pins B² situated in their upper faces, said pins being received in segmental slots C² in the pulleys A², which are mounted on the pulleys D', as before described. When, now, the rotary movement of the pulleys D' brings the pins B² in 80 engagement with either end of the segmental slots C² in the pulleys A², they will be caused to revolve therewith. The pulleys A² are retained in position on the posts by washers a, held in place by pins A⁴, passing through the 90 tenons I, at the extreme upper ends of the posts.

Posts D², located respectively to the right and in front of the gate-frame, and to the left and in the rear thereof, are situated in planes 95 outwardly inclined to the frame-posts, and have peripherally-grooved sheaves E² mounted in their upper ends.

Flexible connection A³, before alluded to as connecting the base-pulleys A², and having 100 counter-weights B² at both ends, after encircling the said pulleys passes over the sheaves

E², mounted in the inclined posts B², which latter have such inclination that they will carry the ends of the ropes aforesaid to such position that they may be manipulated in opening 5 and closing the gates without approaching them closely enough to interfere with them.

Levers A⁵, attached to the said inclined posts D² midway of their lengths, fulfill a two-fold function: first, when counter-weights are 10 used the said levers may be erected to prevent them from swinging unduly; and, second, when the counter-weights are dispensed with, the ends of the flexible connection may be secured to the levers, whereby it may be more 15 easily manipulated.

Vertical posts a' are attached to the inner ends of the gates, at right angles with their lengths. One of said vertical posts has a 20 spring latch-bar, a², attached to its inner face, while the other post, a', has a recess, b, to admit the pin c, which is attached to the latch-bar, and which projects through the vertical post to which it is secured into the recess b in the opposite post, as aforesaid.

25 A cord, d, connects the top of the latch-bar and the loose pulley A, and through the latter operates the latch in locking and unlocking the gate. The elasticity of the latch-bar is such that it will, in its normal position and un-30 influenced by the pulley A², keep the gates locked when closed, or ready to immediately enter into locked adjustment when open.

Inclined blocks d' d' prevent the gates from swinging past each other in closing, and blocks 35 e e prevent them from swinging too far outward when they are opened.

The gate-posts are caused to rotate in opposite directions by making different dispositions of the flexible connections A³ on the pulleys A², and is accomplished by simply arranging the said connection, which may be cord, 40 rope, chain, or other flexible material, to encircle the two loose pulleys A² in different directions. For instance, by passing it around 45 the pulley of the right-hand gate-post from left to right, and around the pulley of the left-hand gate-post from right to left, the pulleys will each impart an opposite rotary movement from their own to the other.

50 Having thus described our invention in detail, we will now proceed to describe its method of operation.

Be it presumed, first, that the gates are closed and locked. The counter-weights are of 55 the same and of such weight as to easily overcome the weight represented by the power required to operate the gates. If, now, the right-hand weight be lifted, the equilibrium between the two weights will be destroyed, the lifted 60 weight will rise, and the left-hand weight will descend. The motion thus induced in the flexible connection will cause the loose pulley of the right-hand gate-post to turn slowly from left to right, and the loose pulley of the left-hand post to turn from right to left. The 65 movement of the latter pulley will operate to overcome the elasticity of the latch-bar and

withdraw its pin from engagement with the vertical post of the right-hand gate. The parts of the gate are arranged to operate in such 70 concert that as soon as the unlatching of the gates is attained the pins located on the lower pulleys, which, it will be remembered, are rigidly secured to the gate-posts, will have reached respectively the outer end of the segmental 75 slot in the right of the loose pulleys and the inner end of the segmental slot in the left of said pulleys. The weights still continuing to move the loose pulleys through the flexible cord, the rigid pulleys, together with the gate-posts and gates, will partake of their opposite motion and be turned in opposite directions, the right-hand gate swinging to the right and the left-hand gate opening to the left. The flexible cord received in the peripheries of the 80 rigid pulleys encircles them both, and transmits any motion that may be imparted to either to the one in repose. The counter-weights being equally heavy, as soon as the lifting force is removed equilibrium will be restored, 85 and the gates will rest at that point of their motion when the restoration of equilibrium took place. Therefore, if they were completely opened, they will remain so without further 90 attention.

To shut the gates through the right-hand end of the flexible connection it is necessary to overcome the equilibrium between the weights by pulling down on that end or weight. The weight represented by the power thus exerted 95 will destroy the equilibrium and shut the gate.

The operation of opening and closing the gates from the rear is exactly the reverse of that necessary to open them from the front approach. For instance, to open the gates the 105 equilibrium must be destroyed by additional weight on the left-hand counter-weight, while to close them it must be destroyed by raising the said weight.

In the foregoing description it has been assumed that the gates are being opened or closed by parties at a distance from them—as, for instance, by a driver without leaving his team, or by an equestrian without dismounting; but it is apparent that a pedestrian may open 110 the gates from either side by simply exerting a pull or pressure directly on the gates themselves. In this latter instance the latch will have to be operated by hand, instead of automatically, as when the gates are operated 115 through the flexible connections or weights.

If desired, we can dispense with one of the loose top pulleys by placing both of the inclined posts on the same side of the gate and providing each post with two sheaves instead 125 of one sheave, as described. In this adjustment the cords will pass over the lower sheave on the inclined posts, then encircle the loose pulley on the gate-post, and from thence over the top sheave on the inclined posts. The ends 130 of the cords or connections are provided each with a light weight, and downward pulls of the cords will in one instance open and in another instance close the gates.

When properly adjusted the different parts of our gate act in such nice concert that, even though the gates be large and heavy, comparatively little power is necessary to open and close them.

Again, our gates combine simplicity of construction and ease of operation with durability in use and comparative cheapness of manufacture and erection.

10 We would have it understood that we do not limit ourselves to the exact construction shown and described, but hold ourselves at liberty to make such slight changes and alterations as fairly fall within the scope and spirit 15 of our invention.

Having fully described our invention, what we claim as new, and desire to secure by Letters Patent, is—

1. In a double gate, the combination, with a 20 frame, of two vertical gate-posts supporting gates, pulleys rigidly secured to the upper ends of the posts, pins located in the upper faces of the fixed pulleys, and loose pulleys having slots in their faces to receive the pins of the fixed 25 pulleys on which they have bearing, substantially as set forth.

2. In a double gate, the combination, with two vertical gate-posts supporting gates and adapted to have rotary movement, pulleys rigidly secured to the upper ends of the posts, 30 loose pulleys having bearing on the fixed pulleys, the motion of one pulley being communicated to the other by a pin-and-slot device, and independent flexible connection between 35 the two sets of pulleys, substantially as set forth.

3. In a double gate, the combination, with two vertical rotating gate-posts supporting gates, of a fixed and a loose pulley mounted 40 on each post, a pin-and-slot device adapting the said pulleys to transmit motion one to the other, and an endless flexible band encircling the fixed pulleys, and a flexible connection encircling the loose pulleys in different directions, 45 substantially as set forth.

4. In a double gate, the combination, with two gate-posts supporting gates, of a fixed and a loose pulley mounted on each post, devices adapting the said pulleys to transmit independent motion to each other whereby the 50 gates are automatically unlocked and swung open in opposite directions, substantially as set forth.

5. In a double gate, the combination, with two vertical rotating gate-posts supporting 55 each a fixed and a loose pulley, of inclined posts having sheaves mounted in their upper ends, levers attached to the inclined posts, and a flexible connection encircling the loose pulleys in different directions and passing over 60 the sheaves in the inclined posts, and counter-weights attached to each end of said flexible connection, substantially as set forth.

6. In a double gate, the combination, with a spring latch-bar attached to one gate and 65 provided with a pin adapted to engage with the other gate and lock it, of a loose pulley, actuated in rotation by a flexible connection between the two pulleys mounted on the gate-posts and cord-connection between one of the 70 loose pulleys and the latch-bar, the rotation of the said pulley operating to spring the latch-bar and unlock the gate.

7. In a double gate, the combination, with a spring latch-bar attached to one gate and 75 provided with a pin adapted to engage the other gate and lock it, of cord-connection between the latch-bar and a loose pulley mounted on one of the gate-posts, the rotation of said pulley operating through the cord to spring 80 the latch-bar and unlock the gate, substantially as set forth.

In testimony that we claim the foregoing we have hereunto set our hands.
